UNITED STATES PATENT OFFICE.

JEAN LOUIS DELORY, OF BLOIS, FRANCE.

ADJUSTABLE GARMENT-CHART.

SPECIFICATION forming part of Letters Patent No. 614,703, dated November 22, 1898.

Application filed December 29, 1897. Serial No. 664,380. (No model.)

To all whom it may concern:

Be it known that I, JEAN LOUIS DELORY, a citizen of France, residing at Blois, Loir-et-Cher, France, have invented certain new and useful Improvements in Apparatus for Drafting Men's Garments, (for which I have obtained Letters Patent in Great Britain, No. 13,711, dated June 3, 1897; in Germany, No. 98,647, dated August 19, 1897; in Belgium, No. 132,241, dated December 3, 1897; in Switzerland, No. 19,012, dated August 5, 1898; in France, No. 273,276, dated December 18, 1897, and in Austria, No. 48/4,243, dated August 6, 1898, filed July 7, 1898,) of which the following is a specification.

This invention relates to an improved apparatus for use in tracing the parts of men's garments—such as coats, waistcoats, and the like—and is so constructed as to give by a simple displacement and adjustment of its parts the fundamental points or lines for a complete tracing of the parts of such garments on cloth or other suitable material of which they are to be made. The said apparatus comprises three distinct parts or sets of adjustable bars, all of which are marked with a scale, the purpose whereof is hereinafter indicated. The first of these pieces serves for the tracing or setting out of the front parts of garments, the second for those of the back, and the third for the small side pieces, where such are used.

For deformed persons it is only necessary to set the apparatus at a higher or lower sign or number, as hereinafter fully explained.

In order that my invention may be readily understood, I will describe the same fully, with reference to the accompanying drawings, in which—

Figure 1 shows the first piece, that for tracing the front; Fig. 2, the second piece, that for the back; and Fig. 3, the third piece, that for the sides. Fig. 4 is a change-bar for use in place of that shown in Fig. 2. Fig. 5 is a section taken on the line xx of Fig. 1, and Fig. 6 is a transverse section taken on the line yy of Fig. 2. Fig. 7 is a longitudinal section taken on the line zz of Fig. 2. Figs. 5, 6, and 7 are drawn to a larger scale than the previous figures.

Referring to the drawings, it will be seen that the front part, Fig. 1, consists of a main

hollow bar or rod A, containing a sliding bar a, adapted to be retained in any desired position by a set-screw a^* . This bar A is provided at a short distance from the lower end with a hollow limb, branch, or arm B, having an angular sliding bar b and set-screw b^* . Upon the angular limb b' of the bar b is a slide C, with set-screw c^* , having arms c' and c^2 , the former of which is hollow and is provided with a set-screw c^3 to enable a sliding bar c^4 , having curved arms c^5 c^6 , to be adjusted as may be required. The arm c^2 is solid and is provided with curved arms c^7 c^8 . 55 60 65

At a short distance from the upper end of the bar A is a hollow branch or limb D, (having a set-screw d^*), in which slides a bar d, to one extremity of which is pivoted a curved bar d' by a pin d^2 . This bar is provided with an index or pointer d^3 near its pivoted end adapted to be set to any of the three radial lines "H," "O," "L" on the sliding bar d, the purpose of which will be hereinafter pointed out. 70 75

The uppermost end of the bar A forms a hollow branch or limb E and is provided with a set-screw e^* for receiving a sliding bar e, to which is pivoted at e' a slightly-curved rod e^2 . 80

To the lower end of the sliding bar a is pivoted at a' a hollow bar F, having set-screws f^1 f^2 , the former of which serves to fix an adjustable sliding bar f^3 , while the latter serves to fix a similar bar f^4 . The bar f^3 carries at 85 its outer end a slightly-curved rod f^4 , pivoted thereto by a pin f^5 .

It will be seen from the drawings that the two bars f^3 f^4 are arranged side by side in the hollow bar F and are capable of being slid in 90 opposite directions the one to the other.

The part for the back (shown at Fig. 2) comprises a hollow main bar G, provided with a set-screw g, in which slides a bar g', carrying at its lower end a rectangular hollow arm g^2 , 95 having a set-screw g^3 , serving to hold an adjustable bar g^4 , formed with a slightly-curved arm g^5 . The hollow bar G is provided near its upper end with a hollow branch or limb M, furnished with a set-screw m and carrying a sliding bar m' , terminating in an angularly-disposed rod m^2 . A sleeve N, adapted to be adjusted on the bar G, is fixed in position by a set-screw n, and in order to prevent this 100

screw scratching or defacing the scale on the bar G a bearing-plate n' , Fig. 7, is interposed between the foot of said set-screw and bar. One end of this plate n' is bent at right angles 5 to form a stop, and it has at its other end a screw n^2 for preventing it becoming detached from the adjustable sleeve N. Extending at right angles from this sleeve is a hollow branch or limb n^3 , furnished with a set-screw n^4 , retaining a sliding bar n^5 . The outer end of 10 this bar is provided with an angular arm n^6 , having a set-screw n^7 for holding an adjustable bar n^8 . The outer end n^9 of this latter is curved, as shown in Fig. 2, and is used for 15 tracing the parts of a coat, while for tracing a jacket or a waistcoat the change-piece, Fig. 4, is substituted therefor.

The part represented in Fig. 3 for the side pieces of coats consists of a hollow bar P, 20 whose upper end P' is curved, and said bar is provided with set-screws p' p^2 at its extremities. The end P' is fitted with a suitably-curved bar p^3 , having a curved arm p^4 . The lower end of the bar P receives an adjustable bar p^5 , having a rectangular hollow 25 arm p^6 , furnished with a set-screw p^7 for holding a sliding bar p^8 , whose outer end carries a slightly-curved arm p^9 .

It may here be mentioned that the three 30 parts are shown in the drawings in their relative positions to each other, but that in practice they would be placed as near as possible to each other, with only sufficient space between them to allow for the passage of the 35 tailor's chalk.

In order to use the apparatus, say for tracing the body part of a coat, the pieces shown in Figs. 1, 2, and 3 are laid on the cloth or other material from which the coat is to be 40 made and are then adjusted in the following manner, according to the measurements previously obtained in the ordinary way with the usual measuring-tape.

It is to be understood that the cloth is double, 45 as usual, and that the apparatus represents the pieces required for one half of the coat, the other half being identical.

Now supposing the measurements taken to be—chest, nineteen inches, one-half being 50 nine and one-half inches; collar, eighteen inches; length of front down to waist, seventeen and one-half inches; length of back down to waist, eighteen inches; girth of waist, thirty-four inches, one-half being seventeen 55 inches; length from armpit to hip, ten inches; armhole, nineteen inches. The bar d in the hollow limb D and the bar n^5 in the branch or limb n^5 are then both adjusted to that division on the scale representing nine and 60 one-half inches or half the chest measurement and are retained thereat by tightening the set-screws d^* n^4 . The bars e and m' are then drawn out as far as the divisions marked 65 “18,” representing the measurement of the collar. The bar a is adjusted to the length at front down to the waist, being here seven-

teen and one-half inches, and the bar g' to eighteen inches for the back. The bars p^3 and p^5 are next adjusted to ten and one-half inches, representing the length from the armpit to the hip. The bars f^2 , f^3 , p^8 , and g^4 are 70 now adjusted to seventeen inches, or one-half the girth at the waist, and the limb F is then turned on its hinge pin or pivot a' , so as to bring the lowest point of the arm f^6 level 75 with p^5 . The bars c^4 and n^8 are next adjusted to the numeral “19” for the armhole, and the points p^8 and n^8 are placed adjacent to the numeral “19” of the scale on the curved arms c^7 c^8 . The bar d' is turned on its pivot d^2 , so 80 as to set the pointer d^3 to the central line “O,” if the person for whom the coat is intended has ordinary shoulders. For persons having high or low shoulders the lines “H” or “L” instead of “O” are used accordingly. It now 85 only remains to set the curved rods e^2 and f^4 by sight, according as whether the person is stout or not. The lines are traced on the cloth by following the contour of the apparatus and completing them from point to point, 90 as indicated by dot-and-dash lines. The lines traced along the curved arms p^4 p^9 and n^9 g^5 form the side seam with the back. For deformed persons the bars a and g' and rods e and f^4 are, as before, adjusted to the required 95 measurements, and the bar d' is set to high or low shoulders, as the case may be.

For tracing a jacket the piece, Fig. 3, is not required, and the upper end of the arm f^6 (marked “V”) is brought to a level with the 100 bar g^4 , while the curved bar n^9 is replaced by that shown in Fig. 4 for the side seam.

It is thus evident that the apparatus can be set in a few moments to any measurement and to suit various forms of garments, thus 105 obviating the necessity of having a large number of patterns, while at the same time the chance of making mistakes in setting out is reduced to a minimum.

Having now particularly described and explained the nature of my said invention, and in what manner the same may be employed, I declare that what I claim is—

1. In an apparatus for drafting men's garments, a section for tracing the front part of 115 the garment, consisting of a hollow main bar A provided with the hollow arms B, D and E, limbs a, b, d and e adapted to enter said bar and arms, means for securing said limbs in said bar and arms, bars attached to said limbs 120 for indicating the position of the cut for the front of the garment, the position of the armhole, and the position of the lower edge of the front of the garment, and a shoulder-bar pivoted at one end to the section and having 125 its opposite end free, whereby said shoulder-bar is adapted to be moved independently for indicating the position of the shoulder-cut, substantially as set forth.

2. In an apparatus for drafting men's garments, a section for tracing the front part of 130 the garment, consisting of a hollow main bar

A provided with the hollow arms B, D and E, limbs a , b , d and e adapted to enter said bar and arms, means for securing said limbs in said bar and arms, bars attached to said limbs 5 for indicating the position of the armhole, the position of the shoulder-cut, and the position of the cut for the lower edge of the front of the garment, and curved rods, the one pivoted at one end to said latter bar and the other to the limb e , and adapted by direction 10 toward each other to produce the curve for the front of the garment, substantially as set forth.

3. In an apparatus for drafting men's garments, a section for tracing the back part of the garment, consisting of a hollow main bar G provided with the hollow arms M and n^3 , limbs g' , m' and n^5 adapted to enter said hollow bar and arms, said limbs g' and n^5 being 15 provided with hollow portions at their outer ends, angular limbs g^5 and n^9 adapted to enter said hollow portions, means for securing the limbs in the main bar and hollow arms, means 20 for securing said angular limbs in said hollow portions, and a substitution-piece adapted for 25 insertion into the hollow portion of the limb n^5 , the angle of said substitution-piece being greater than the angle of the angular limb n^9 , whereby said apparatus is adapted for

drafting a vest or waistcoat, substantially as 30 set forth.

4. In an apparatus for drafting men's garments, a section for tracing the back part of the garment, consisting of a hollow main bar G provided with the hollow arms M and n^3 , 35 limbs g' , m' and n^5 adapted to enter said hollow bar and arms said limbs g' and n^5 being provided with hollow portions at their outer ends, angular limbs g^5 and n^9 adapted to enter 40 said hollow portions, means for securing the limbs in the main bar and hollow arms, means for securing said angular limbs in said hollow portions, and an adjusting device connected to the arm n^3 for adjusting said arm on the main bar, said adjusting device consisting of 45 a sleeve adapted to slide on the bar G, a setscrew in said sleeve, and a bearing-plate between said screw and the bar G, said bearing-plate extending beyond said sleeve, and a screw for retaining the bearing-plate in position 50 in the sleeve, substantially as set forth.

In testimony that I claim the foregoing as my invention I have signed my name in presence of two subscribing witnesses.

JEAN LOUIS DELORY.
